REFRIGERATOR CAR

Ralph B. Winship, Montreal, Quebec, Canada, assignor, by mesne assignments, to Standard Railway Refrigerator Company, a corporation of Delaware

Application July 31, 1937, Serial No. 156,659

15 Claims. (Cl. 62—17)

The invention relates to refrigerator cars for handling perishable commodities.

The objects of the invention are to provide a refrigerant container adaptable to hold solid refrigerants, such as wet ice, dry ice, or a liquid refrigerant, such as brine (salt water) and to form such refrigerant container and associate it with the other elements of a car so that the circulating refrigerating air may move below or around and also through the container and be cooled by the refrigerant, thus causing the air to circulate by convection, through flues and channels provided for the purpose. Refrigerant containers, such as the usual brine tank, are now made with solid bottoms, tops and side walls so that the circulating air moves outside thereof and in contact therewith, but not in direct contact with the refrigerant. By allowing the circulating air to directly engage the refrigerant the heat transfer from the air to the refrigerant is greatly increased and the temperature of the circulating air is lowered, and the convection movement of the air is augmented, thus increasing the efficiency of the refrigerating system.

Another object is to provide an insulated partition or pan to catch the liquid refrigerant which splashes through the air circulating apertures in the tank and drains it into vertical air circulating flues in the wall of the car, from whence it is drained outside of the car, but which in the meantime further cools the air in the vertical flue.

Another object is to position the air circulating apertures in the refrigerant tank so that the ventilating air entering the roof hatchway may move through as well as around the refrigerant tank.

Another object of the invention is to provide a series of beams or carlines extending between opposite walls of the car to constitute meat racks and also constitute means for supporting a refrigerant container, preferably near the roof of the car. (Carcasses of animals are preferably suspended in a refrigerator car by meat-hooks engaging meat racks near the ceiling of the car. Refrigerant containers are sometimes placed near the ceiling of the car and flues are provided to direct the cool circulating air down through the side walls and thence upwardly around the carcasses.)

Another object is to provide a metallic meat rack carline of great strength for its weight, and further to provide means to carry off moisture or condensation so that it will not come in contact

with the meat nor floor of the car, and a further object is to form the last mentioned means so that it will support the meat rack carline upon the wall of the car.

In the drawings:

Fig. 1 shows a half cross section of an upper part of a railway car having my improvement and is taken on line 1—1 of Fig. 3.

Fig. 2 shows a section through the vertical wall of the railway car on line 2—2 of Fig. 1.

Fig. 3 shows a longitudinal section of the railway car on line 3—3 of Fig. 1.

The drawings illustrate my invention adopted for use in what is known as the top bunker refrigerator car; that is, wherein the refrigerant chambers or tanks 2 are positioned adjacent to the roof 3 of the car and provided with hatchways 4 for loading the chambers with a refrigerant. The hatchways are provided with the usual lids 6 and plugs 7. The drawings show the plugs 7 attached to the lids 6. Any convenient positioning 9 or locking mechanism 10 may be used with the lids.

A series of refrigerant chambers or tanks 2 is positioned on each side of the center line 11 of the car so as to extend substantially the full length thereof. The roof 3 is preferably provided with insulation 13 between and around the hatchways. A metallic roof 16 is provided over the insulation to protect the insulation from moisture and to assist in resisting the tendency of the car to weave due to the motion thereof. The roof shown comprises metallic sheets 16 extending from eave 17 to eave 17 of the car and overlapping the side plates 18 and preferably secured thereto by the angle 19 in the usual manner. The adjacent margins of adjacent sheets are provided with upstanding flanges 21 which are covered by a cap 22 and the rivets 23 secure the cap 22 and flanges 21 together. The roof sheet 16 is cut out at the hatchways and provided with an upstanding flange 24 adjacent the hatch insulation 25. The hatchway shield 26 extends upwardly inside of the hatch insulation 24 to protect the insulation. A cap 28 covers the hatch insulation 25, shield 26 and roof flange 24. The refrigerant chamber 2 is provided with an inclined upwardly projecting flange 30 around the refrigerant feeding opening which underlies the hatch shield 26.

A preferably downwardly and outwardly sloping partition or ceiling 33 is positioned below each row or series of refrigerant chambers 2 and spaced therefrom so as to provide a downwardly inclined flue 34 below the refrigerant chambers. 55

The partitions or ceilings 33 on the opposite sides of the car are separated adjacent to the middle of the car 11 to provide an air channel 36 between the lading compartment of the car and the flues 34 below the chambers. An upstanding wall 37 is provided on each side of the air channel 36 with the tops 38 of these walls positioned above the lower part 39 of the chambers. This downwardly inclined flue 34 communicates 10 with the vertically extending flue 40 in or adjacent to the side wall of the car, which flue 40, in the form illustrated, is between the side wall partition 41 and the side wall itself 42. Each side of the side wall flue 40 is preferably lined 15 with a preferably galvanized thin metallic sheet 43—44 to retain the moisture within the flue, and also each side of this side wall flue may be lined with a layer of Sisalkraft paper 45—46 or some other light insulating material to prevent 20 leakage of heat.

Any convenient floor rack may be used to provide a space between the lading and the floor of the car, which space communicates with the side wall flues 40.

25 In such a refrigerator car the refrigerant in the chambers 2 cools the air surrounding them so that, due to the increased weight and density, the air moves down the downwardly and outwardly inclined ceilings 33 (that is, in the 30 flues 34 between the ceiling 33 and the refrigerant chamber 2) into the side wall vertical flues 40, and thence into the space between the floor rock and the floor of the car, and then upwardly through openings in the floor rack and between 35 or through the lading, and being warmed thereby, rises and passes through the air channel 36 between the sloping ceilings 33 and thence around the refrigerant chamber 2, and being cooled thereby, repeats the cycle. Such cooling and 40 heating of the air is continuously repeated. A further desirable feature of such construction is that the side wall flues 40 provide a blanket of cooled air around the lading and the water on the floor of the car also keeps the floor cold. Ice, 45 salted ice, brine, dry ice or any of the usual refrigerants may be used in such a system. The arrows indicate the air movement.

My improved refrigerant container or tank 2 is provided with a solid or imperforate bottom 50 45 and the lower parts 46 of the side walls thereof are also solid or imperforate, while the upper parts 47 of some or all of the side walls are perforated or provided with apertures 50—51 whereby the circulating air may come in direct 55 contact with the refrigerant so as to increase the capacity of the device for cooling the circulating air. The lower parts 46 of the side walls of the containers are solid so as to retain the brine within the tank so as to obtain the maximum heat absorbing capacity therefrom. This 60 advantage would also be obtained from the melted ice when a solid ice is used. Experience shows that a little brine left in the car while the car is being unloaded keeps the lading cool 65 while being inspected and unloaded. When desired the brine or melted ice may be run into the vertical flues 40 through the drain 48 which is controlled by the drain valve handle 49.

The beam or carline 60 extends between and 70 is secured to the opposite walls 42 of the car and comprises an arched or apexed compression member 61 consisting of a web 62 and depending flanges 63 and an arched or apexed tubular section tension member 65 preferably made of 75 a tube slightly flattened with the tension and

compression members connected by spaced apart struts 66 extending between and secured to such members. These beams or carlines constitute combined meat rack and refrigerant tank supports (the spacers 68 between the tank and the 5 ceiling are positioned over these beams or carlines). These beams 60 also hold the side walls in their proper relative position by preventing them from coming together or separating. They also support the roof of the car. 10

The struts 66 and compression members 61 form recesses 69 for the reception of the meat hooks 70 which support the carcasses of animals. The struts 66 are positioned so that the carcasses will be spaced apart to allow circulation 15 of air between.

The carlines 60 are supported by the angular members 73 extending lengthwise of the car which, in turn, are supported by vertically disposed posts 74 in the side wall flue 40. Condensed moisture, which forms on the metallic beams, runs downwardly and is caught within the gutter formed by the upwardly inclined arm 76 and the vertical arm 77 of the angular member 73. The water is drained into the side wall 25 flue 40 through apertures 79 in the partition 41 and arm 76.

The accompanying drawings illustrate the preferred form of the invention, though it is to be understood that the invention is not limited to 30 the exact details of construction shown and described, as it is obvious that various modifications thereof, within the scope of the claims, will occur to persons skilled in the art.

I claim:

1. In a refrigerator car having spaced apart walls, each wall comprising vertical posts with a partition secured to said posts to provide vertical flues between the posts, each wall provided with a horizontally disposed member secured to 40 a plurality of said posts and provided with an upwardly inclined arm, an arched metallic beam extending between and secured to the members on the opposite walls which rests upon and is secured to said upwardly inclined arms, apertures in said partitions substantially flush with the upper surfaces of the arms which communicate with the vertical flues whereby condensed moisture on said metallic beam follows the beam to the upwardly inclined arm and flows through 50 said apertures into said vertical flues.

2. In a refrigerator car having spaced apart walls, each wall comprising vertical posts with a partition secured to said posts to provide vertical flues between the posts, each wall provided 5 with a horizontally disposed member secured to a plurality of said posts, an arched metallic beam extending between and secured to the members on the opposite walls, each of said members provided with an upwardly inclined arm positioned below the end of said metallic beam to catch the moisture of condensation, and means to drain said moisture into said flues.

3. In a refrigerator car, the combination of 6 a roof, spaced apart walls each provided with 7 a vertical flue, a refrigerant container adjacent said roof and adjacent one of said walls, a ceiling below said container, spacers supporting the container upon said ceiling and in spaced relation thereto to provide a flue therebetween which 7 communicates with the adjacent side wall flue, and a beam below each spacer and parallel therewith, which beam extends between and is supported by said spaced apart walls.

4. In a refrigerator car, the combination of 7

5 a vertical wall, a vertical flue associated with said wall, a refrigerant container adjacent said wall, and an insulated partition below said container and spaced therefrom to provide a substantially horizontal flue communicating with said vertical flue so that the air in said horizontal flue, being cooled by a refrigerant in said container, induces a circulation of air through said flues, the bottom and lower parts of the 10 sides of said refrigerant container being solid with the upper parts of certain of said sides provided with apertures, whereby a liquid refrigerant in said container will spill over said solid parts and pass through said horizontal and vertical flues thereby further cooling air circulating in said flues.

6 5. In a refrigerator car, the combination of a vertical wall, a vertical flue associated with said wall, a refrigerant container adjacent said wall at a higher elevation than said flue and a partition below said container and spaced therefrom to provide a substantially horizontal flue communicating with said vertical flue so that the air in said horizontal flue being cooled by 20 a refrigerant in said container induces a circulation of air through said flues, the bottom and lower parts of the sides of said refrigerant container being solid with the upper part of one of said sides provided with an aperture, whereby a liquid refrigerant in said container will spill through said aperture and pass through said vertical flue thereby further cooling air circulating in said vertical flue.

7 6. In a refrigerator car having a refrigerant container above the lading compartment, a vertical flue associated with a vertical wall of said car, and a partition below said container and spaced therefrom to provide a substantially horizontal flue communicating with said vertical flue so that the air in said horizontal flue being cooled by a refrigerant in said container induces a circulation of air through said flues, the bottom and lower parts of the sides of said refrigerant container being solid with the upper part of 40 one of said sides provided with an aperture, whereby a liquid refrigerant in said container will spill through said aperture and pass through said vertical flue thereby further cooling air circulating in said vertical flue, means to drain a liquid refrigerant from said container to said vertical flue, and a closure for said means operable from within said lading compartment.

8 7. In a refrigerator car, the combination of a roof, spaced apart walls, a vertical flue associated with one of said walls, a refrigerant container adjacent said roof, a ceiling spaced below said container to provide a substantially horizontal flue therebetween communicating with the vertical flue, a metallic carline supporting said ceiling which extends between and is secured to said walls, and means to drain condensate which forms on said metallic carline into said vertical flue.

9 8. In a refrigerator car having a refrigerant container above the lading compartment, a vertical flue associated with a vertical wall of said car, and a partition below said container and spaced therefrom to provide a substantially horizontal flue communicating with said vertical flue so that the air in said horizontal flue being cooled by a refrigerant in said container induces a cir-

culation of air through said flues, means to drain a liquid refrigerant from said container to said vertical flue, and a closure for said means operable from within said lading compartment.

10 9. A structure as defined in claim 5 wherein the bottom of the refrigerant container slopes downwardly toward said vertical wall so that when part of the liquid refrigerant spills into the horizontal flue the remaining refrigerant will be adjacent the vertical flue. 10

11 10. A structure as defined in claim 5 wherein the bottom of the refrigerant container slopes downwardly toward said vertical wall so that when part of the liquid refrigerant spills into the horizontal flue the remaining refrigerant will be adjacent the vertical flue, and means to drain the refrigerant from the container into said vertical flue. 15

12 11. A structure as defined in claim 4 wherein the lower parts of said apertures are on a substantially horizontal line. 20

13 12. A structure as defined in claim 4 wherein the side of said container adjacent said car wall is provided with apertures so that some of said liquid refrigerant will spill directly into said vertical flue. 25

14 13. In a refrigerator car, the combination of a vertical wall, a vertical flue associated with said wall, a refrigerant container with one side thereof adjacent said flue, and an insulated partition below said container and spaced therefrom to provide a substantially horizontal flue communicating with the vertical flue so that air in the horizontal flue being cooled by a refrigerant in said container induces a circulation of air through said flues, the bottom and lower parts of the sides of said container being imperforate with the upper parts of the side of the container adjacent the vertical flue and the side of the container remote from the vertical flue both being provided with apertures, whereby a liquid refrigerant in said container will spill over said solid parts and pass through the horizontal and vertical flues thereby further cooling the circulating air and also whereby air may pass over the refrigerant in the container into the vertical flue. 40

15 14. In a railway refrigerator car, the combination of a roof, spaced apart walls, a vertical flue associated with one of said walls, a refrigerant container adjacent said roof, a ceiling below said container, spacers supporting the container upon said ceiling and in spaced relation thereto to provide a flue therebetween which communicates with said flue, and beams below said spacers and parallel therewith, said beams extending between and supported by said walls. 55

16 15. In a refrigerator car, the combination of a vertical wall, a vertical flue associated with said wall, a refrigerant container adjacent said wall at a higher elevation than said flue, and means to direct circulating air into substantial contact with said container and thence into said flue thereby cooling said air and inducing a downward flow of air through said flue, said container being formed to retain liquid refrigerant in the lower part thereof and to overflow some of said liquid refrigerant from said container into said flue during service movements of the car thereby further cooling said air. 60

RALPH B. WINSHIP. 70
